FEEDING MEANS FOR GRID PASTING
MACHINES

John E. Brown and Aldie B. Clark, Cleveland,
Ohio, assignors to Willard Storage Battery
Company, Cleveland, Ohio, a corporation of
West Virginia

Application May 14, 1931, Serial No. 537,344

13 Claims. (Cl. 198—20)

This invention relates to improvements in feeding means for grid pasting machines.

One of the objects of the invention is the provision of automatic feeding means of this character, simple in form and dependable in operation.

Another object is the elimination of all feeding belts, and the provision of positive means for inducing the travel of the grids independently of each other.

Another object is the provision of a rapidly acting pusher for quickly conducting a grid delivered from the magazine into the grid conveying means, the pusher then returning to its original position.

Another object is the provision of means for stopping the magazine feed independently of other parts of the machine.

Still another object is the provision of means for agitating or jarring the stack of grids in the magazine to overcome any adherence of one grid to another caused by burrs on the trimmed edge, slightly roughened surfaces, or the like, and also to assist gravity in working the grids downwardly upon their ways and to free adjoining grids from each other at the lower end of the magazine, where the pressure caused by the weight of the grids above is considerable.

A further object is the provision of means for automatically stopping the magazine feed and grid conveyor in the event that two grids one above the other are delivered into the conveying means.

Other objects and features of novelty will appear as we proceed with the description of those embodiments of the invention which, for the purposes of the present application, we have illustrated in the accompanying drawings, in which

Figure 1 is an elevational view, partially in vertical section, of a portion of a grid pasting machine embodying the invention.

Fig. 2 is an end view of the same, showing the grid magazine in side elevation.

Fig. 3 is a perspective view on a larger scale of a fragment of the magazine showing one of the lifting fingers.

Fig. 4 is a plan view of that portion of a grid pasting machine which is shown in Fig. 1.

Fig. 5 is an end view of a modified form of the invention, showing the magazine in side elevation, and

Fig. 6 is a front view of the magazine shown in Fig. 5.

Similar reference characters refer to like parts throughout the views.

In the drawings, we have illustrated the first portion only of a grid pasting machine, the frame of which comprises posts 10 and horizontal spaced channel bars 11. The path of the grids, marked G, in their travel through the machine lies principally between these two channel bars.

A paste hopper A is located directly above a pasting plate 12, and is spaced therefrom just enough to permit a grid to pass between the hopper and plate, the forward end of the plate 12 being beveled off to facilitate this entrance of the grids into the space between the hopper and plate. Within the hopper there may be mounted a bladed wheel 13 which is rotated to force the paste through the interstices of the grids, the plate 12 serving as a backing for stopping the paste and spreading it out on the under side of the grid, as it travels over the plate.

Beyond the paste hopper the pasted grids are caused to pass between scrapers and wipers in order to remove excess paste and to thoroughly compact the paste retained in the grids. One such wiper is shown in Fig. 4.

The details of the grid pasting part of the machine and of the grid feeding means immediately in advance of and beyond the paste hopper are not claimed herein but certain features thereof are claimed in a companion application Serial No. 35,088 filed August 7, 1935 as a continuation in part of the present application.

At the front end of the machine, to one side of the channel bars 11, there is mounted a grid magazine B and associated grid delivery mechanism. In the form shown in Figs. 1 to 4 inclusive, this magazine comprises a frame 15 having inclined upper rails 16 over which the lugs C of the grid G are adapted to run, and inclined ways 17 upon which the lower edges of the grids rest and by which they are principally supported. In the forward end of each of the rails 16 there is formed a recess which is covered by a stop plate 18 that is secured to the rail 16 by any suitable means. This recess, covered by the stop plate 18, forms a slot in which is received a lift finger 19 of a thickness slightly less than the depth of the slot, and also slightly less than the thickness of one of the grids G. These fingers are preferably made of steel, and are formed at their lower ends with eyes by means of which they are mounted upon pins 20 carried at the forward ends of ejector bars 21 that are pivotally mounted at their rear extremities upon pins 22 carried by the magazine frame 15. Near the forward ends of rails 16, at a distance behind stop plates 18 only slightly greater than the

thickness of one grid G, there are mounted top stops 23. These stops at the rear are flared upwardly as indicated at 24, so that as the grids descend along the ways, if any of them are supported out of contact with the ways by burrs or rough surfaces on adjoining plates, the flared surfaces 24 will serve to wedge them down to the desired position.

The shaft through which power is furnished to the magazine delivery mechanism is shown at 25. It carries a spur gear 26 to which driving force is imparted through a gear reduction unit 27 which comprises a shaft 28 upon which is mounted a gear 29 that meshes with a gear 30 on the shaft of an electric motor 31. Shaft 25 carries a bevel gear 32 that meshes with a bevel gear 33 on a shaft 34 that is mounted beneath the magazine 15 and extends transversely across the channel bars 11, having bearings supported by said bars.

On one face of the bevel gear 33 there is a cam surface 35, against which runs a cam follower 36 that is mounted upon the lower side of a yoke 37 having vertical end portions attached to the ejector bars 21, as indicated at 38 in Fig. 2. As the cam 35 rotates, the high spot thereof swings yoke 37 to the right, as viewed in Fig. 2, causing the ejector bars 21 to swing upon their pivots 22 and thereby raise the lift fingers 19. The cam and follower 35, 36 constitute a separable drive connection. They may be held apart by an eccentric 39 pivotally mounted on the forward end of frame 15 and engaging beneath one of the ejector bars 21, a handle 40 being attached to the eccentric 39 for the convenient operation of the latter. By this means the lift fingers 19 may be locked in their elevated positions in order to interrupt the delivery of grids from the magazine, without stopping the drive and operation of the balance of the machine.

At the forward lower end of magazine 15 there is located a stop 41 which engages the lower edge of the foremost grid until the latter is lifted over it by the upward motion of the lift fingers 19, this motion also serving to elevate the grid lugs above the stop plates 18. The grid then drops down onto a track mounted midway between the channel bars 11, the track in this instance consisting of side ledges 42 carried by the channel bars. An angle bar 43, mounted on one of the channel bars 11, serves to prevent the grids from falling too far to the right, as viewed in Fig. 2.

Beneath the channel bars 11 opposite the magazine B there are carried two angular brackets 44 which support a channeled casting 45 running parallel with the bars 11 and halfway between them. In this casting there is pivotally mounted the lower end of a pusher finger 46. A short distance therefrom there is also pivotally mounted the lower end of a lever 47, the upper end of which carries a cam follower, running upon a cam 48 keyed to shaft 34. The pusher finger 46 and the lever 47 are joined by an adjustable link 49. Pusher finger 46 is urged toward the right, as viewed in Fig. 1, by a spiral spring 50. Through the greater part of the rotation of shaft 34 the pusher finger 46 is held in the position illustrated in Fig. 1, but when the lever 47 rides into the low spot of cam 48, spring 50 pulls pusher finger 46 to the right, in that figure, with a rapid motion, and the finger engaging the rear edge of a grid G on the ledges 42, pushes the grid rapidly toward the right. Immediately thereafter the cam 48 returns lever 47 to the position illustrated

in Fig. 1, and the pusher finger 46 is thereby returned to its initial position.

Referring now to the conveying means for causing the travel of grids G along a path between the channel bars 11, there are mounted at regular intervals above and below the path of travel pairs of superposed shafts 51 and 52, the shafts 52 having fixed bearings carried by the channel bars 11, and the shafts 51 having bearings in blocks 53 which are vertically adjustable by means 10 of screws 54 or the like, in order to regulate the tractive engagement of the conveying means with the grids, and in order to accommodate grids of different thicknesses. Each pair of shafts 51, 52 are geared together by means of intermeshing 15 spur gears 55. Both shafts are positively driven by means of bevel gears 56 carried by the shafts 52 meshing with bevel gears 57 carried by shaft 25. Each shaft 51 and 52 has mounted thereon a pair of knurled feed wheels 58 which are spaced 20 apart transversely far enough to engage only the border portions of the grids, the wheels 58 of the upper shaft being spaced from those of the lower shaft just enough to receive the grids between them with enough friction to produce a 25 good tractive engagement. It will be noted by reference to Figs. 1 and 4 that we have located one set of knurled feed wheels directly in front of the pasting plate 12 and another set directly behind that plate. The longitudinal dimension 30 of the plate 12 is less than that of one of the grids, and the longitudinal distance between sets of feed wheels is less than the longitudinal dimension of a grid, so that there is always positive feeding movement imparted to each grid at 35 all times, this being particularly important in connection with the travel of the grids over the pasting plate 12. Furthermore no grid is ever subjected to strains imposed upon it by having to push along any grid or grids in front of it.

The throw of the pusher finger 46 is sufficient to advance a grid delivered from the magazine into contact with the first set of feed rolls 58. However it will be observed that the pusher finger 46 is operated by spring pressure rather than 45 positively, so that in the event that any obstacle should be interposed to prevent the travel of the grid, the pusher finger would do no damage. Furthermore, the spring continues the application of pressure to the rear end of the grid until 50 the latter is well gripped by the feed wheels 58.

In Figs. 5 and 6 we have illustrated a somewhat different form of magazine and grid delivery mechanism. The track upon which the grids travel through the first part of the machine is 55 also somewhat different, comprising a series of supporting rails 59 arranged between and parallel with the channel bars 11. The feed wheels 58 are mounted on their shafts just outside of this track. The magazine comprises a frame 60 having upper rails 61 which constitute fixed ways adapted to support the lugs on the grids. At their forward ends these rails are formed with slots of the same character as those in the rails 16 of the first described form of the invention, 65 adapted to receive with a loose sliding fit lift fingers 62 which, like the lift fingers 19, are of a thickness less than the thickness of one of the grids. The outer wall of each slot is formed by a plate 63 which is secured to the forward end of 70 the rail 61 by studs 64 or the like. Each of these plates carries a downwardly and forwardly inclined guide arm 65, the upper rear end of which constitutes a stop having a function similar to that of stop plate 18, previously referred to. The 75

lower ends of the lift fingers 62 are bent rearwardly at a right angle and are loosely mounted in slots formed in the forward extremities of ejector bars 66 which are pivotally mounted at 5 67 upon the magazine frame. These bars 66 function in a manner similar to the bars 21 of the first described form of the invention. They extend rearwardly beyond their pivotal mountings however and have pivotal connection at their 10 rear extremities with connecting rods 68 that are attached to eccentric straps 69 running upon eccentrics 70 carried by the shaft 25.

At the rear of the frame 60 we mount a pair of agitator bars 71 upon pivot pins 72 which extend downwardly toward the front end of the frame in a direction approximately parallel with the rails 61. These agitator bars in their lower position clear the grids carried by the rails 61, but in their upper position they raise the grids 20 slightly so as to lift the lugs thereof clear of the rails 61. The oscillating movement of these bars is effected by means of connecting rods 73 which are pivotally joined at convenient points with the bars 71 and are attached at their lower extremities to eccentric straps 74 which run upon eccentrics 75 also keyed to shaft 25. The eccentrics 70 and the eccentrics 75 are set at an angle to each other, however, so that the upward travel of the lift fingers 62 precedes by a short interval 25 the upward movement of the agitator bars 71.

The shaft 25 also carries a cam 76 having a relatively wide face, upon which travels a follower wheel 77 that is mounted at the outer end of an arm 78 carried by and keyed to a shaft 79 which extends at right angles to shaft 25 and is supported in bearings carried beneath the channel bars 11. On the shaft 79, midway between the channel bars 11, there is keyed a pusher finger 80 similar to the pusher finger 46. This finger is urged forward by a coil spring 81 which is attached at 82 to some suitable frame element. The circular part of cam 76 normally holds follower 77 in the position illustrated in Figs. 5 and 6 against the tension of spring 81. When the low spot of the cam approaches the follower 77, however the latter is permitted to descend, travelling across the face of the cam to a lower position and enabling the spring 81 to swing the pusher 80 forward to advance a delivered grid 50 upon the tracks 59 into contact with the feed wheels 58.

In front of the forward end of the magazine we mount a lower stop 83 with which the lower edge of the foremost grid is adapted to contact. 55 When the grid is lifted by the lift fingers 62 to clear the upper stops, the lugs at the upper corners of the grid run upon the curved upper edge surface of the guides 65, and these guides are so formed that they exert a lateral pull upon the 60 grid lugs when the grid approaches horizontal position, thereby pulling the lower edge of the grid up over the stop 83.

At one side of the grid track there is a bracket 65 84 in which is mounted a rock shaft 85 carrying an arm 86 in the outer end of which is mounted a feeler 87, consisting conveniently of a wheel or roller that is adapted to run upon the upper surfaces of the grids passing over the track. The shaft 85 on one side of the bracket has attached thereto an arm 88 upon which there is an adjustable weight 89. At the opposite end of the shaft 85 there is an arm 90, the outer extremity of which is threaded to receive an adjustable post 91, having on its upper end a cap 92 of insulating material. The cap 92 being urged upwardly

by weight 89 acting through lever 88 and arm 90, is caused to close an electric switch of any suitable form. As illustrative of such switch we have shown herein two flexible metallic fingers 93 and 94, the cap 92 pressing the finger 93 against the 5 finger 94 to close an electric circuit through conductors 95 and 96, which are arranged to control directly or indirectly the flow of current to motor 31. When the feeler 87 rises a very small distance only, as when it rides over inaccuracies in 10 the surface of a grid, thereby depressing cap 92 slightly, the metal fingers 93, 94 follow the cap 92 downwardly without separating. However if the feeler 87 is lifted a greater distance, as when it rides over two superposed grids, the cap 92 is 15 depressed a considerable distance and the fingers 93, 94 separate, breaking the circuit 95, 96 which controls the driving motor, thereby stopping the machine so that the trouble can be corrected before any damage is done. 20

Operation.—Before the machine is started, the magazine B is filled entirely or partially with skeleton grids, and the paste hopper A is filled with paste. The foremost grid in the magazine then occupies the space directly behind stop plates 25 18 and in front of top stops 23, the lower edge of the grid being held back of the upper edge by the stop 41. The motor is then started and the shaft 25 caused to turn. In the case of the magazine construction of Fig. 2, the cam 35 then 30 swings the yoke 37 forward, rocking ejector bars 21 upwardly and causing lift fingers 19 to rise until the grid lugs clear the stop plates 18 and the lower edge of the grid clears the stop 41. The top stops 23 prevent more than one grid at 35 a time from being raised by the lift fingers. The overbalanced grid then falls forward onto the track consisting of ledges 42, the side guide 43 preventing the grid from falling too far forward. The cam 48 is so positioned on the shaft 34 that 40 it permits forward motion of pusher finger 46 as soon as the grid is in place on the track. The grid is then pushed forward by the spring actuated pusher 46 into the first set of knurled feed wheels 58. These wheels being positively driven 45 immediately carry the grid forward at a predetermined rate of speed. As the knurled wheels run upon the border portions of the grids, no damage is done to the fragile inner structure of the latter. The movement of the grid under the influence of 50 spring 50 is rapid, and is timed so as to space the grids apart for their further travel through the machine a short distance only. The pusher finger then rapidly returns to its initial position where it is held through the greater part of each 55 revolution of the shaft 34. In the meantime also the ejector bars 21 and the lift fingers 19 have returned to their position illustrated in Fig. 2, and the stack of grids has slid down to bring the foremost one against the stops 18 and 41 and 60 out from under the top stops 23. Should anything occur which would tend to interfere with the proper functioning of the machine, the operator may stop the delivery of grids to the conveying means by swinging the handle 40 to operate the eccentric latch 39, thereby holding the lift fingers 19 in their upper position.

The grid delivery mechanism of Figs. 5 and 6 is quite similar in operation to that of Figs. 1 and 2, although the angle of inclination of the 70 ways may be considerably less than that of Figs. 1 and 2, due to the fact that gravity is assisted by the operation of agitator bars 71 in working the grids down toward the delivery end of the magazine. The grids in this case are supported 75

normally by their lugs resting upon the inclined fixed rails 61. The top stops 97 are positioned far enough above the rails 61 to accommodate the upper edges of the grid lugs when the grids are raised by the movement of bars 71. This movement toward the top stops also serves to depress any grids which are supported above their proper position by frictional contact with adjacent grids. In Fig. 5 the bars 71 are shown in their raised position, as are also the fingers 62. The high points of the two eccentrics 70 and 75 are spaced apart about a quarter revolution, the upward movement of the bars 71 preceding that of the fingers 62. The upward travel of the grids, induced by the upward swing of bars 71, is not sufficient to lift the grid lugs above the level of the upper stops, that is to say the rear ends of guide arms 65. Hence there is no possibility of the second grid falling forward over the guides 65. Furthermore, the lift fingers 62 would be in the way of such a movement.

As previously explained, the forward edge surfaces of the guide arms 65 are not merely arcs of circles struck from a point corresponding with the lower edge of the foremost grid. On the contrary the lower forward ends of these guides extend forwardly far enough to act as cam surfaces for exerting a forward pull on the grid lugs as gravity draws the grids downward, and by this means the lower edges of the grids are pulled over the bottom stop 83.

The grids in their travel downwardly through the magazine are supported first upon the fixed rail 61 and then upon the swinging bars 71 alternately. Between each upward and downward motion of the bars 71 a grid is delivered from the magazine. When that occurs, and the fingers 62 have descended, the upper edges of the grids swing forward a distance equal to the thickness of one grid, the lower edges being restrained by friction against the bars 71 which are supporting the weight of the grids at that time. Then when the bars 71 swing to their lower position the grids are lowered so as to cause their weight to be supported by their lugs from fixed rails 61, whereupon the lower edges of the grids swing forward a distance corresponding to the thickness of one grid to bring the foremost grid into contact with the stop 83. This forward movement of the grids by a tilting action working first in one direction and then in the other we have found to be most effective. It serves to loosen up the contact between the grids at the forward end of the magazine where the weight of the grids above exerts considerable pressure tending to make the grids stick together, and it serves to work apart adjacent grids which are inclined to stick together because of burrs, surface roughnesses, or the like.

In the foregoing description we have necessarily gone somewhat into detail in order to explain fully the particular embodiments of the invention herein illustrated, but we desire it to be understood that such detail disclosures are not to be construed as amounting to limitations, except as they may be included in the appended claims.

Having thus described our invention, we claim:

1. In a machine of the class described, a grid magazine comprising inclined ways adapted to support a series of twin grids with the lugs up, stops at the forward end of the magazine against which the foremost lugs engage, and lift fingers movable up and down directly behind said stops and beneath the foremost lugs for the purpose

of engaging the foremost lugs and raising the foremost grid to clear said stops, whereby the grid is delivered from the magazine.

2. In a machine of the class described, a grid magazine comprising inclined ways adapted to support a series of twin grids with the lugs up, stops at the forward end of the magazine against which the foremost lugs engage, and lift fingers of a thickness less than the thickness of a grid movable up and down directly behind said stops and adapted to engage the lower edges of the foremost lugs for the purpose of raising the foremost grid to clear said stops, whereby the grid is delivered from the magazine.

3. In a machine of the class described, a grid magazine for supporting a series of twin grids edgewise for movement by gravity in a downwardly inclined path, said frame comprising a pair of inclined side rails over which the lugs of the grids run, stops at the forward ends of said rails against which the lugs of the foremost grid engage, and lift fingers movable upwardly beneath the foremost lugs for the purpose of engaging the foremost lugs and raising the foremost grid to clear said stops.

4. In a machine of the class described, a grid magazine having inclined ways over which the grids are adapted to slide on edge, stops adapted to engage the foremost grid, lift fingers for raising the foremost grid to disengage it from said stops, whereby it is adapted to drop forward by gravity, a track upon which the delivered grid drops, a pusher for sliding the delivered grid upon said track, and associated timed operating mechanism for raising said lift fingers and subsequently advancing said pusher and lowering said lift fingers.

5. In a machine for handling storage battery grids, a magazine having parallel inclined ways spaced apart upon which a series of twin grids may be supported edgewise, means for delivering grids from said ways one by one, and means acting directly upon the grids for moving them up and down in the magazine, whereby they are jarred into contact with said ways.

6. In a machine of the class described, a magazine having inclined ways upon which the lugs of twin grids are adapted to slide, an agitator bar mounted in the magazine adapted to engage the lower edges of the grids and running approximately parallel to said ways, stops at the forward end of the magazine, means for lifting one grid at a time over said stops, and means operating intermittently for actuating said agitator bar to momentarily lift said grids out of contact with the ways.

7. In a machine of the class described, a magazine frame having inclined ways upon which the lugs of twin grids may slide, an agitator bar pivotally mounted at the rear of said frame and extending forwardly in a direction approximately parallel to said ways, said bar in its lower position clearing the lower edges of grids supported upon the ways, means for delivering grids one at a time from the forward end of the magazine, and means for swinging said agitator bar upwardly to engage the bottom edges of the grids and lift the grids off said ways momentarily.

8. In a machine of the class described, a magazine frame having inclined ways upon which the lugs of twin grids may slide, an agitator bar pivotally mounted at the rear of said frame and extending forwardly in a direction approximately parallel to said ways, said bar in its lower position clearing the lower edges of grids supported

- upon the ways, stops at the forward end of the magazine for engaging the foremost grid, means operating at regular intervals for swinging the said agitator bar upwardly to engage the bottom edges of the grids and lift the grids off said ways momentarily, the grids in the forward end of the magazine receiving the maximum agitation, and means following closely thereafter for lifting the foremost grid clear of said stops.
9. In a machine of the class described, a grid magazine comprising means for supporting a series of twin grids edgewise for movement by gravity in a downwardly inclined path, said means including upper and lower elements each adapted to support the weight of the grids independently of the other, one of said elements comprising a fixed rail and the other comprising a movable agitator bar approximately parallel to said fixed rail, and means for moving said agitator bar upwardly and downwardly, whereby the grids are supported alternately upon said upper and lower elements, and whereby as grids are removed from the forward end of the magazine one at a time gravity causes the upper and lower edges of the grids remaining in the magazine to work downwardly alternately as the points of support change from lower to upper and vice versa.
10. In a machine of the class described, a grid magazine comprising inclined ways adapted to support a series of twin grids with the lugs up, upper stops at the forward end of the magazine against which the lugs of the foremost grid engage, a lower stop at the forward end of the magazine of greater height than the upper stops and against which the lower edge of the foremost grid engages, means operating periodically for lifting the forward grid sufficiently to cause the grids to clear said upper stops, and guides extending downwardly and forwardly from said upper stops over which the lugs on each grid are caused to run as the upper edge of the grid

swings downwardly due to gravity, said guides inclining forwardly far enough to pull the lower edge of each grid over said bottom stop as the grid moves toward horizontal position.

11. In a machine of the class described, a magazine having inclined ways upon which the lugs of twin grids are adapted to slide, an agitator bar mounted in the magazine adapted to engage the lower edges of the grids, stops at the forward end of the magazine, means for lifting one grid at a time over said stops, and means for actuating said agitator bar to momentarily lift said grids at regular intervals out of contact with the ways.

12. In a machine of the class described, a horizontal grid track, moving means adapted to engage the upper and lower surfaces of the grids for positively feeding them along said track at a predetermined rate of speed, a grid magazine arranged adjacent said track, mechanism for delivering grids one at a time from said magazine onto said track to the rear of said feeding means, and means operating at regularly timed intervals for pushing each delivered grid into said feeding means, whereby the grids are caused to move over the track in evenly spaced relation.

13. In a machine of the class described, a grid magazine comprising inclined ways adapted to support a series of twin grids with the lugs up, stops at the forward end of the magazine against which the foremost lugs engage, lift fingers movable up and down directly behind said stops and beneath the foremost lugs for the purpose of engaging the foremost lugs and raising the foremost grid to clear said stops, and a pair of guides inclined forwardly and downwardly from said stops over which the lugs on each grid are caused to run as the upper edge of the grid swings downwardly due to gravity.

JOHN E. BROWN.
ALDIE B. CLARK. 40
